UNITED STATES PATENT OFFICE.

ANNIE L. BOHER, OF CHICAGO, ILLINOIS.

STORMPROOF VEIL.

1,076,809.

Specification of Letters Patent. Patented Oct. 28, 1913.

Application filed December 6, 1912. Serial No. 735,273.

To all whom it may concern:

Be it known that I, ANNIE L. BOHER, a citizen of the United States, residing at Chicago, in the county of Cook and State 5 of Illinois, have invented certain new and useful Improvements in Stormproof Veils, of which the following is a specification.

This invention relates to a stormproof 10 veil or head covering; and has for its object to provide an article of this character that is more especially intended for the protection of hats and at the same time present an appearance similar to that of an ordinary veil.

15 Many valuable hats are damaged and often entirely ruined when the wearer is caught out in a sudden shower or storm without being provided with convenient means for protecting a hat or other head- 20 wear.

The figure in the drawing is a plan embodying the improved features.

A represents the veil part proper which 25 may be of the usual open work fabric or material. The middle part B may be composed of any suitable waterproof cloth or rubber fabric that will best serve the purpose. The border C may be composed of 30 any suitable material the same as the balance of the veil, or made plain or of an ornamental design.

The design shown in the drawing is used 35 as illustrating one form or pattern of the invention; so that it will be understood that the dimensions, relative proportions and arrangement of the several parts may be changed as practical workings may require.

It is not intended that the improved veil shall take the place of or become a substitute for the ordinary every day article in 40 general use. The present invention is to fill a distinct emergency requirement of its own in affording convenient protection for ladies' hats in stormy weather.

The central part or waterproof section B, 45 set in the body of the veil, will be of such dimensions as to properly cover a hat, leaving the veiling ends or parts to be draped to present the dressy effect of the ordinary veil. The veiling fabric may be made to 50 cover the inset waterproof part if so desired.

The article can be folded up compactly and carried in a handbag or other receptacle 55 ready for convenient use.

Having thus described my invention, what I claim is—

1. As a new article of manufacture, a veil provided with a stormproof part or section set in the body of the veil. 60

2. As a new article of manufacture, a veil composed of part veiling fabric, and a stormproof fabric section.

3. A veil provided with a stormproof part or section. 65

4. A veil, having its respective ends composed of veiling fabric connected by an insert part composed of a stormproof fabric.

In testimony whereof I affix my signature in presence of two witnesses.

ANNIE L. BOHER.
